UNITED STATES PATENT OFFICE.

PERRY H. CAZIER, OF NASHVILLE, MICHIGAN, ASSIGNOR TO POSTUM CEREAL CO., LIMITED, A PARTNERSHIP ASSOCIATION ORGANIZED UNDER THE LAWS OF THE STATE OF MICHIGAN, OF BATTLE CREEK, MICHIGAN.

ADVERTISING TWINE-HOLDER.

1,187,499.

Specification of Letters Patent. Patented June 20, 1916.

Application filed November 9, 1915. Serial No. 60,528.

To all whom it may concern:

Be it known that I, PERRY H. CAZIER, a citizen of the United States of America, residing at Nashville, in the county of Barry 5 and State of Michigan, have invented certain new and useful Improvements in Advertising Twine-Holders; and I do hereby declare the following to be a full, clear, and exact description of the invention, such as 10 will enable others skilled in the art to which it appertains to make and use the same.

This invention relates to twine holders. And an object and purpose of the invention consists in the provision of a twine 15 holder having a movable take-up device secured to which is a member having a flat surface of considerable area on which may be imprinted an advertisement or the like, whereby with the movement of the take-up 20 device attention will be called to the advertisement.

A further object of the invention consists in providing a construction which can be made very economically at an extremely 25 low cost to the manufacture, yet which will be efficient and durable, having few parts, none of which are liable to get out of order.

To these ends I have embodied my invention in the construction shown in the 30 accompanying drawing, in which:

Figure 1 is a perspective view of the complete advertising twine holder. Fig. 2 is a front elevation thereof. Fig. 3 is a plan view; and Fig. 4 is a fragmentary detail 35 view with parts in section illustrating the pivotal attachment of the take-up device to the frame of the twine holder.

Like reference characters refer to like parts throughout the several views of the 40 drawing.

In the construction of the twine holder a flat bar of metal is used which is bent to form a vertical section or support 1 having at its lower and upper ends sections 2 and 45 3 extending at right angles from the vertical support. On the lower section a cone-shaped ball of twine 4 wound upon a core 5 is detachably mounted. The upper section 3 has a loop 6 struck upwardly therefrom by means of which the device as a whole may be suspended from any convenient support. Substantially midway between the upper and lower ends of the support 1 a take-up lever 7 is mounted having

one end turned at right angles as shown 55 at 8 and the opposite end turning back upon itself as indicated at 9. An intermediate portion of the lever is bent inwardly at 10, this portion lying in close contact with the support 1 and a shouldered rivet 11 passes 60 through both members to effect the pivotal connection of the lever to the support 1. The lever moves freely upon the pivot and by reason of the weighted end at 9 this end will naturally tend to seek the lowest level. 65 I have provided a stop 12 in the shape of an open eye adjacent the lower end of the support 1 against which the weighted end of the lever may strike to prevent too far movement of the lever about its pivot. A 70 thin flat disk 13 is secured to the lever 7 by screws 14 as shown. The disk preferably is of circular outline though it is not limited to any particular shape. Any desired advertising matter may be imprinted upon 75 the front side of the disk as will be readily apparent. A series of openings, three in number, are formed in the end of the section 3 through which is threaded the twine 16 from the ball of twine 4. The twine is 80 interwoven among the openings so that as it is drawn through there is some frictional resistance to the passage of the twine in this manner making a simple yet effective tension. The twine leads to the lower end 85 of the support 3 passing through an opening 17 therein, and then to the angularly bent end 8 of the upper lever 7 passing through the opening 18, being then carried 90 through the eye of the stop 12. The holes 19 shown in the lower section 2 may be used 95 to receive screws or the like in attaching the twine holder to any support underneath it if desired.

In withdrawing the twine from the twine 95 holder the end of the twine 16 is grasped and a pull exerted thereon, the first effect and of which is to rotate the lever 7 and its attached member 13 about the pivot 11 bringing the opening 18 and the opening in the eye 12 in alignment whereupon the twine may be drawn directly through openings 17, 18 and 12 and as much withdrawn as desired. As soon as the twine is released 100 the lever returns to its normal position as shown in Fig. 1, elevating that part of the twine below the eye 12, taking it up and 105 out of the way, while the tension through

the openings 15 holds the twine from unwinding from the ball.

From the foregoing it will be apparent that I have provided an exceedingly simple yet effective twine holder and one in which the movable take-up lever may be utilized as a support for a comparatively large disk or like member on which advertising may be imprinted. The parts of the twine holder may be formed readily from flat metal, and at low cost.

Slight modifications in structural detail may be resorted to without departing from my invention which is defined in the appended claims and, accordingly, I do not wish to be limited to the exact specific structure shown.

I claim:—

1. In combination, a support formed from a flat bar of metal having sections bent at right angles at the upper and lower ends of the support, a lever pivotally mounted between its ends on the support, said lever being formed from a flat bar with one end bent at right angles to the body of the bar and the opposite end bent back upon itself

to provide a weight, means for supporting a quantity of twine, said twine threading through the upper section, the lower end of the support and the angularly bent end of the lever, an eye positioned at the lower end of the support through which the twine leads, and a flat member attached to the lever, substantially as described.

2. In combination, a vertical support provided with an opening adjacent its lower end, a lever formed from a flat bar pivotally mounted on the support, one end of said lever being bent at right angles to the body of the bar and having an opening therein and the other end bent back upon itself to provide a weight, whereby when twine is threaded through said openings in the support and lever and a pull is exerted on the twine the lever will be rotated about its pivot, and a disk detachably secured to the lever and movable therewith, substantially as described.

In testimony whereof I affix my signature.

PERRY H. CAZIER.
